UNITED STATES PATENT OFFICE.

LASZLO REIDER, OF CLEVELAND, OHIO.

BOTTLE-CLOSURE.

1,068,077.

Specification of Letters Patent.

Patented July 22, 1913.

Application filed December 18, 1912. Serial No. 737,447.

To all whom it may concern:

Be it known that I, LASZLO REIDER, a subject of the King of Hungary, residing at Cleveland, in the county of Cuyahoga and State of Ohio, have invented certain new and useful Improvements in Bottle-Closures, of which the following is a specification, reference being had therein to the accompanying drawing.

10 This invention relates to bottle closures, and the primary object of my invention is to provide a closure for bottles embodying a screen that serves functionally as a cage and sieve, as a cage supporting a portion 15 of the closure and as a sieve straining liquid placed in or removed from the bottle provided with the closure.

Another object of this invention is to provide a closure for a bottle that can be 20 opened without resorting to the use of a corkscrew or other instrument, and at the same time wired or sealed to provide a permanent closure.

A further object of this invention is to 25 accomplish the above results by a mechanical construction that is simple, durable and applicable to various kinds of receptacles.

With the above and other objects in view the invention resides in the novel construction, combination and arrangement of parts 30 to be hereinafter more specifically described and then claimed.

Reference will now be had to the drawing, wherein:—

35 Figure 1 is a vertical sectional view of a bottle closure showing the same in a closed and sealed position, Fig. 2 is a similar view illustrating a closure in an open position, Fig. 3 is a horizontal sectional view taken 40 on the line III—III of Fig. 1, Fig. 4 is a similar view taken on the line IV—IV of Fig. 2, and Fig. 5 is a side elevation of a detached screw.

45 Describing my invention in detail with reference to the drawing, wherein like numerals denote corresponding parts throughout, 1 denotes a bottle neck and arranged in said bottle neck is a cage 2 made of interwoven wire constituting a foraminous 50 body. Extending into the cage 2 in proximity to the lower end thereof is a stopper 3 having a peripheral flange 4 that is secured to the neck of the bottle to hold the

stopper and the cage 2 therein. These two elements are permanent and cannot be removed without disfiguring the bottle neck. The bottle neck 3 is provided with a central longitudinal bore 5 having the walls thereof 55 screw threaded and the lower end of the bore terminates in a frusto-conical shaped 60 seat 6.

7 denotes a frusto-conical shaped plug loosely mounted in the cage 2 and said plug has a threaded opening 8 alining with the bore 5. The plug is covered by a piece of 65 rubber 9 or other resilient material and this piece of rubber insures a nonleakable connection with the plug 7 in engagement with the seat 6.

10 denotes a screw having a head 11 provided with a peripheral flange 12. The head 11 has a transverse opening 13 the purpose of which will presently appear. The screw 10 can be screwed into the bore 5 and the opening 8 to elevate the plug 7 and close 70 the stopper 3.

14 denotes a piece of wire or seal extending through the opening 13 and engaging the bottle neck 1, said piece of wire or seal locking the head of the screw relatively to 80 the bottle neck whereby the screw cannot be removed.

To prevent the plug 7 from rotating while being elevated, the bottom of the plug is provided with depending pins 15 that extend through the cage, as shown in Figs. 1 and 2.

The closure can be made of various kinds of material and the invention is susceptible to such changes as fall within the scope of 90 the appended claim.

What I claim is:—

In a bottle closure, the combination with a bottle neck, of a cage located within the bottle neck and provided with a foraminous 95 bottom, a stopper mounted in said bottle neck and having its inner end spaced from the bottom of the cage, said stopper provided with a centrally disposed threaded bore terminating in a centrally disposed 100 frusto-conical seat, the inner end of the bore opening into the smaller end of said seat, a frusto-conical plug loosely supported by the cage and having a threaded opening and further provided with depending guide pins 105 permanently projecting through said bot-

tom, a headed threaded member engaging with the threads of the stopper and plug for moving the plug to engage the seat, said head having a transverse opening, 5 means extending through said opening and engaging the bottle neck for securing said member to the bottle neck.

In testimony whereof, I affix my signature in the presence of two witnesses.

LASZLO REIDER.
